UNITED STATES PATENT OFFICE

2,683,880

APRON

Thelma Krigbaum, San Fernando, Calif.

Application March 3, 1952, Serial No. 274,598

1 Claim. (Cl. 2-48)

1
This invention relates to work aprons for use by women in industrial plants. In the average factory or industrial plant most women wear slacks covered by an apron. If punch presses or other machinery are operated, the operator's legs often must be raised, with the result that the apron binds or otherwise interferes with free leg movement. The present invention is directed to a type of apron which permits free movement of the legs in walking or in lifting the legs.

An object of the invention is the provision of an industrial work apron so formed as to readily be separable to permit leg movement, while at the same time protecting the inner garment worn by the wearer.

Another object is the provision of an industrial work apron which does not require frequent washing in order to maintain a clean outer appearance.

Primarily, the invention contemplates an apron which is attractive in appearance, affords full protection to garments, is economical in cost to manufacture and is generally superior to aprons now worn by women in industrial plants.

In the drawing:

Fig. 1 is a front elevation of the apron;

Fig. 2 shows the apron of Fig. 1 with certain of its parts in detached relationship;

Fig. 3 is a fragmentary elevation showing the means of attachment between the separable parts of the apron; and,

Fig. 4 is a view similar to Fig. 3 but showing a shifting of the front panels of the apron.

Referring now to the drawing:

The improved industrial apron is shown in one embodiment in Fig. 1 and designated as 1. The same is formed in two parts or sections, as shown in Fig. 2, at 2 and 3. These parts are separable. Part 2 includes a bib 4, a front panel 5 seamed to or otherwise secured to or forming a continuation of bib 4, and a side panel 6, seamed to or forming an extension of the front panel and of the same length as the front panel, that is, the side panel 6 extends from the waist to the hem portion 7 for both panels. A belt 8 is secured at the waistline to panels 5 and 6 and extends beyond the side edge 9 of panel 6. Detachable straps 10 and 11 are secured to the bib 4.

The section 3 includes front and side panels 12 and 13 identical in form with panels 5 and 6, the said panels 12 and 13 having secured at the waistline thereof a belt 14 which extends beyond the edge 15 of panel 13, with both panels hemmed at 16. To secure the parts or sections in working relationship I may utilize buttons, snaps or other quick detachable elements. For the purpose of illustration, however, I have shown buttons. The belt portion secured to panel 5 is provided with a pair of buttons 17 positioned in staggered relationship with button holes 18 adjacent said buttons. The same construction and spacing of buttons and button holes is provided

2
for the belt 14 secured to panel 12 as shown at 19 and 20. When panel 5 overlies panel 12, the buttons 19 are passed through button holes 18 and pairs of buttons appear as shown in Fig. 1. When panel 12 overlies panel 5, the buttons 17 are passed through button holes 20, see Figures 3 and 4. One or the other of the belt members 8 or 14 is provided with a button hole 21 and a button 22, whereby the belt may be secured about the waist. The straps 10 and 11 carry buttons 23 at each end thereof, which are adapted to be passed through button holes 24 in the bib 4 and button holes 25 and 26 in the belts 8 and 14. Preferably the straps are in crossed relationship at the back of the wearer.

Other features may consist in the provision of pockets 27, 28, 29 and 30.

The operation, uses and advantages of the invention are as follows:

While the operation is undoubtedly understood from the description previously given, it may be said that the wearer of the apron may fasten the same about the waist with either front panel outermost. If the outermost panel becomes soiled or damaged or otherwise unusable, this panel may be shifted so as to position the other panel thereover. Thus as shown in Figs. 3 and 4, panel 5 may overlie panel 12, or vice versa, and the buttons allow ready attachment of the panels, and one that is secure. It is also noteworthy that regardless of the shifting of the panels the pockets remain on the outside of the apron.

By permitting a complete separation of the panels, as illustrated in Fig. 2, it is evident that the legs may be moved to any desired position, such as might be necessitated in the operation of machines in a factory, without in any manner binding the legs. The separation permitted would be equal to the width of the two front panels, and the legs are therefore protected by the panels at all times.

I claim:

A work apron formed in two parts, each part provided with a front panel of substantially the same form and size, and with a side panel, each part provided with a belt portion, one of said parts provided with a bib in alignment with the front panel thereof, and means at the belt portion of each front panel for detachably interconnecting the said front panels in working relationship and in such a manner that either front panel may overlap the other front panel.
